UNITED STATES PATENT OFFICE.

ANDREW W. STEIGER, OF BRIDGEPORT, CONNECTICUT, ASSIGNOR TO YOST WRITING MACHINE COMPANY, OF ILION, NEW YORK, A CORPORATION OF NEW YORK.

TYPE-WRITING MACHINE.

SPECIFICATION forming part of Letters Patent No. 747,259, dated December 15, 1903.

Application filed April 8, 1901. Serial No. 54,894. (No model.)

To all whom it may concern:

Be it known that I, ANDREW W. STEIGER, a citizen of the United States, and a resident of Bridgeport, in the county of Fairfield and 5 State of Connecticut, have invented certain new and useful Improvements in Type-Writing Machines, of which the following is a specification.

This application relates to the type actions 10 of writing-machines.

Generally the key-lever system is of greater width than the type-bar system, laterally-inclined connecting-rods being used in some cases between the side key-levers and type- 15 bars, and the levers of other machines being crowded together so as to bring them within a space as nearly equal as possible to the width of the type-bar system.

The main object of my invention is to avoid 20 the necessity of unduly crowding the key-levers together or of using inclined connections at the sides of the machine, which have a more or less cramping effect upon the key-levers and produce uneven wear on the type- 25 bar pivots.

To these and other ends my invention consists in certain combinations of devices, features of construction, and arrangements of parts, all as will be hereinafter fully set forth, 30 and particularly pointed out in the concluding claims.

In the accompanying drawings, in which my improvements are shown in connection with the type system of a Yost writing-machine, Figure 1 is a sectional elevation taken 35 longitudinally of the machine. Fig. 2 is a section taken transversely of the machine and about centrally of the type system. Figs. 3 and 4 are side and front elevations of a key- 40 lever hanger or post. Fig. 5 is a sectional detail of a joint. Fig. 6 is a fragmentary sectional plan of a portion of the key-levers and their type-bar connections. Fig. 7 is a dia- 45 grammatic plan of the key-lever and type-bar system. Fig. 8 is a plan of a blank used in forming a connecting-rod. Fig. 9 is an edge view of a complete connecting-rod.

In the several views portions of the machine are omitted or broken away to more 50 clearly disclose the invention, and similar

parts are designated by similar numerals of reference.

Each of the type-bars comprises arms 1 and 2 and a link 3, pivoted upon the free ends of said arms and having at its free end a type 55 4, which normally contacts with an ink-pad 5, whence it may be swung upon said arms to make an impression upon the under side of the platen 6, as illustrated at Fig. 2. The arms 1 are pivotally supported at their inner 60 disk-like ends upon a hollow annulus 7, which is fixed upon a bracket 8. The arms 2 are pivoted at their outer ends upon a fulcrum-wire 9 and work in radial slots 10 cut in a ring 11. Said arms 2 are connected by rods 65 12 to key-levers 13 of the first order, said levers being pivoted between their ends upon pins 14, projecting laterally from hangers or posts 15, which are riveted at 16 upon the under side of a horizontal plate 17, which forms 70 a portion of the base of the machine, spring-keepers 18 being riveted at 19 to the sides of said hangers to prevent accidental displacement of the levers from their fulcrum-pins, while enabling the detachment of any lever 75 when desired. Each lever is provided with a wire returning-spring 20 and a finger-key 21, the latter having a hollow stem 22, which works in a perforated guide-bar 23 and a guide-hole 24, formed in said plate 17. Said 80 stem is connected to the lever by an attaching-piece 25, which is forked to bestride the forward end of the key-lever, and is provided with a pin 26 to engage a short horizontal slot 27, formed in the forward end of the key-lever. The arms of the fork are made separable for permitting detachment of the lever, and the attaching-piece is formed with an upwardly-extending stem 28 for insertion into the open lower portion of the tubular key- 85 stem 22.

The upper end of the connecting-rod 12 is pivoted at 29 to the type-bar arm 2, and the lower end thereof is connected by an attaching-piece 25 to the rear end of the key-lever, 95 the latter being horizontally slotted at 30.

To the lower portion of each rod 12 is pivoted at 31 the outer end of one of a series of horizontal links 32, the inner disk-like ends 33 whereof are arranged in an annular bear- 100

ing-groove of C cross-section formed by centrally - arranged upper and lower grooved plates 34 and 35, which are clamped together and held upon a boss 36 by a screw 37, said boss being cast or fixed upon the base-plate 17. The links 32 are of equal length and radiate from the bearing-ring 34 in directions corresponding with the radial positions of their associated type-bars. The outer ends 10 31 of the forwardly and rearwardly extending links 32 at the middle of the machine lie almost directly over the rear ends of the key-levers with which they are associated, their connecting-rods extending about vertically 15 from the key-levers to the type-arms, as illustrated at Fig. 1. The width of the key-lever system being, however, greater than the diameter of the circle of vertical connecting-rods 12, the levers at the sides of the machine lie at increasing distances outside of 20 said circle. These outlying levers are connected to the vertical rods 12 by means of lateral arms or offsets 38, extending radially outward from the latter and varying in length 25 according to the positions of their respective levers. At its outer end each offset is formed with a downwardly-directed thimble or socket 39 for receiving the stem of an attaching-piece 25, by which said offset is connected to 30 the key-lever. The upper end of the rod 12 is folded and bifurcated at 40 to straddle the type-bar arm 2, the tines of the fork being yielding, so as to enable the detachment of the rod from the type-bar. The shouldered 35 rivet 31 is provided with a large head to prevent undue sway of the links 32 and 12.

When a key is depressed, its lever is vibrated upon the fulcrum 14 and the rod 12 is thrust upwardly, thereby swinging the 40 arm 2 and causing the type to be impressed upon the platen or the paper thereon. The keys have substantially uniform dips, and the key-levers have substantially uniform movements at their rear ends, including those 45 key-levers which are arranged at the sides of the machine and connected to the offsets 38. Since the rods 12 are pivoted upon the type-bar arms 2 and the links 32, all parts of said rods, including the offset arms 38, have substantially uniform vertical movements, and the outlying key-levers are equally effective with those at the center of the system 50 in operating the type-bars. It will be seen that if a link should be connected to an extreme outlying key-lever and extended diagonally upward to its type-bar without being guided at its lower end independently of the key-lever there would occur at the operation of the key a lateral thrust upon the 55 key-lever which would cramp the same and impede its movement; but by having the link 12 positively guided by a separate device cramping action is avoided, and hence the key-levers may be placed at any desired 60 distance from the center of the machine, the offsets 38 being correspondingly lengthened.

Upon the guiding-links 32 I arrange an an-

nular universal bar 42, which is connected by arms or spokes 43 to a central vertical rod 44, to which is fixed a collar 45, which rests upon a hub formed by the union of said spokes. When any type-bar is operated and its associated link 32 swung upwardly, as at Fig. 2, the portion of the annular universal bar 42 which rests upon the actuated link 75 is elevated, the diametrically opposite portion thereof remaining at rest and having a bearing upon the opposite link 32, whereby said universal bar is enabled by acting as a lever of the second order to lift the collar 45 and rod 44, which by a nut 46 thereon lifts the inner end of a forwardly-projecting arm 47, formed upon a dog-rocker 48, which is pivoted at 49 to a bracket 50. Said rocker is provided with a returning-spring 51 and carries at its upper end both a detent-dog 52 and a feeding-dog 53, the latter being in engagement with an escapement-wheel 54, which is connected by a pinion 55 and rack 56 to any suitable platen-carriage 57, propelled by a 80 spring-barrel 58, to which it is connected by a strap 59. Upon said movement of the dog-rocker the feeding-dog is disengaged from the escapement-wheel and the detent-dog engaged therewith, and upon the subsequent 85 return of the type-bar and universal bar to normal position said dog-rocker vibrates in the reverse direction and permits an advance movement of the carriage in the usual manner.

From the foregoing description it will be understood that the rods 12 at the sides of the machine with their offset portions 38 constitute angular rods or links which are connected at their ends to the arms 2 and to the 90 levers 13 and that these rods comprise each horizontal and vertical arms.

Various changes may be made within the scope of the invention, some parts whereof may be used without others.

What I claim as new, and desire to secure by Letters Patent, is—

1. In a type-writing machine, the combination of a type-operating arm, a key-operated lever, a connecting-rod extending from said lever to said arm, said connecting-rod comprising vertical and horizontal arms, and a guiding-link pivoted at one end to said connecting-rod and at the other end to a fixed portion of the machine.

2. In a type-writing machine, the combination of a series of type-operating arms, a series of key-operated levers extending beneath said arms, a series of connecting-rods extending upwardly from said levers to said arms, said connecting-rods comprising each vertical and horizontal arms, and a series of guiding-links arranged below the type-bars, each of said guiding-links being connected at one end to one of said connecting-rods and extending laterally therefrom and being pivoted at the other end upon a fixed part of the machine.

3. In a type-writing machine, the combina-

tion of a series of type-operating arms arranged in a curve, a series of key-operated levers, a series of connecting-rods each attached at one end to a type-arm and at the other end to a lever, said connecting-rods comprising each vertical and horizontal arms, and a series of radially-arranged guiding-links pivoted to said connecting-rods.

4. In a type-writing machine, the combination of a series of radially-arranged type-operating arms, a series of connecting-rods attached at their ends to said arms, said connecting-rods comprising each vertical and horizontal arms, a series of guiding-links pivoted to the opposite ends of said connecting-rods and having a support upon the framework, and a series of key-operated levers directly connected to said connecting-rods.

5. In a type-writing machine, the combination of a type-carrying arm, a rod attached at one end to said arm, a guiding-link extending laterally from the opposite end of said rod and supported upon a fixed part of the machine, an offset arm upon said rod extending in the opposite direction from said link, and a key-operated lever directly connected to the free end of said offset arm.

6. In a type-writing machine, the combination of a radially-arranged type-carrying arm, a connecting-rod pivoted at one end thereto, a radial link pivoted to the opposite end of said rod and extending inwardly therefrom, a radial offset arm extending laterally from said rod, and a key-operated lever connected to the free end of said offset arm.

7. In a type-writing machine, the combination of a pivoted type-carrying arm, a connecting-rod attached thereto and extending downwardly therefrom, a radially-arranged link pivoted at its outer end to the lower end of said connecting-rod and extending inwardly therefrom, an outwardly-extending offset arm fixed upon said connecting-rod, and a horizontal key-lever connected to the free end of said offset arm.

8. In a type-writing machine, the combination of a pivoted type-carrying arm, a link pivoted upon a fixed part of the machine, a connecting-rod attached to said arm and to said link, a key-operated lever, and an attaching device engaged at one end to said lever and at the other end to said connecting-rod.

9. In a type-writing machine, the combination of a type-carrying arm, a connecting-rod pivoted at one end thereto, means for guiding the other end of said rod, an offset formed upon said rod, and a key-operated lever connected directly to said offset.

10. In a type-writing machine, the combination of a series of radially-arranged type-carrying arms, a series of radially-arranged links connected to the framework, a series of connecting-rods extending from said arms to said links, a series of key-operated levers, and offset arms of varying lengths extending laterally from said connecting-rods and connected to said key-operated levers.

11. In a type-writing machine, the combination of a series of radially-arranged type-carrying arms, a series of radially-arranged links connected to the framework, a series of rods connecting said arms to said links, a series of key-operated levers, and offset arms of varying lengths extending radially from said rods and connected to said key-operated levers.

12. In a type-writing machine, the combination of a series of radial type-carrying arms arranged in a curve, a series of key-operated levers, a series of connecting-rods engaging said type-carrying arms, a series of radially-arranged inwardly-extending links pivoted at their outer ends to said connecting-rods, offsets of varying lengths extending laterally from the connecting-rods at the sides of the system, and a series of key-operated levers, some of which are attached to said offsets and others of which are attached directly to the connecting-rods.

13. In a type-writing machine, the combination of a type-operating arm, a key-operated lever, a connecting-rod attached at one end to said type-operating arm, a guiding-link pivoted to said connecting-rod, an offset upon said connecting-rod, a thimble as formed upon said offset, and an attaching device having both a stem for insertion into said thimble and a fork for engaging said key-operated lever.

14. In a type-writing machine, the combination of a type-operating arm, a key-operated lever, a connecting-rod extending from said lever to said arm, a guiding-link pivoted at one end to said connecting-rod and having a support upon the framework of the machine, a bar arranged in the path of said guiding-link, a letter-feeding mechanism operated by said bar, and a carriage.

15. In a type-writing machine, the combination of a carriage, escapement devices therefor, a series of type-operating arms, a series of key-operated levers extending beneath said arms, a series of connecting-rods extending upwardly from said levers to said arms, a series of guiding-links arranged below the type-bars and each connected at one end to one of said connecting-rods and extending laterally therefrom and having a support upon the framework of the machine, and a universal bar operated by said guiding-links and connected to said escapement mechanism.

16. In a type-writing machine, the combination of a carriage, escapement devices therefor, a series of type-operating arms arranged in a curve, a series of key-operated levers, a series of connecting-rods each attached at one end to a type-bar and at the other end to one of said levers, a series of radially-arranged guiding-links attached to said guiding-rods, and an annular universal bar operated by said guiding-links and connected to said carriage-feeding devices.

17. In a type-writing machine, the combi-

nation of a carriage, escapement devices therefor, a series of radially-arranged type-carrying arms, a series of radially-arranged links supported upon the framework, a series 5 of connecting-rods extending from said arms to said links, a series of key-operated levers, offset arms of varying lengths extending laterally from said connecting-rods and connected to said key-operated levers, an annular universal bar supported upon said links, and connections from said universal bar to said carriage-feeding devices.

18. In a type-writing machine, a key-lever post, as 15, having attaching means, as 16, a 15 fulcrum 14 extending laterally from said post, and a spring-keeper, as 18, riveted to said post.

19. In a type-writing machine, the combination with a series of keys and a series of 20 type-bars, of a series of key-levers each fulcrumed between its ends upon a pin 14 projecting laterally from a fixed post 15 and held in place by a spring-keeper 18, a series of rods, each connected at one end to one of said type- 25 bars and at the other end formed with a thimble for receiving the stem of an attaching device 25 which is forked to bestride the end of a key-lever, and a series of tubular stems for the keys, each of said stems being open at its 30 lower end to receive the upwardly-projecting stem of a similar forked device which bestrides the forward end of the lever.

20. In a type-writing machine, the combination of a carriage, escapement devices therefor, a system of type-bars, a system of rods attached at their upper ends to said type-bars, guiding-links extending inwardly from the 35 lower portions of said connecting-rods, offsets formed upon the rods at the sides of the sys- 40 tem, a system of horizontal levers of the first or-

der detachably connected directly to said rods by means of devices 25, the levers at the sides of the system being connected to said offsets, posts 15 upon which said levers are detachably mounted, said posts being provided with 45 spring-keepers 18, and key-bearing stems detachably connected to the forward ends of said levers.

21. In a type-writing machine, the combination of a type-bar comprising pivoted members 1, 2 and 3, a key-lever, an angular connecting-link connected to the type-bar and key-lever, and a guide-link connected to said connecting-link.

22. In a type-writing machine, the combination of a type-bar, a key-lever, an angular connecting-link connected to the type-bar and key-lever, and a guide-link connected to said connecting-link, one member of said angular connecting-link extending outwardly to compensate for the differences in position of the 60 type-bar and key-lever.

23. In a type-writing machine, the combination of a system of type-bars, a system of key-levers of greater width than the system 65 of type-bars, angular connecting-links between the type-bars and key-levers at the sides of the systems, one member of each of said links extending outwardly to compensate for the differences in width of the systems of type-bars and key-levers, and a guide-link connected to each angular connecting-link.

Signed at the borough of Manhattan, in the city of New York, in the county of New York and State of New York, this 4th day of April, 75 A. D. 1901.

ANDREW W. STEIGER.
